UNITED STATES PATENT OFFICE

2,370,641

METHOD OF FORMING REAR AXLE HOUSINGS

Clarence L. Dewey, Elkhart, Ind.

Application July 16, 1942, Serial No. 451,159

2 Claims. (Cl. 29—153.1)

The housing of the present invention is designed for use in automobiles or similar vehicles, and in conformity with the customary practice makes provision for the mounting and enclosing of the differential gearing and shafting for driving the rear wheels of an automobile or the like.

The invention is directed to the shaping of the axle housing arms from tubular steel sections which in the main are tapered and otherwise configured in conformity with the method set forth and described in the Dewey patent, No. 2,265,723, issued December 9, 1941, with slight additional fabrication to adapt the sections thus formed for connection with an intermediate "banjo" section which may be electrically or otherwise welded or attached to the tubular arms to give to the housing as a whole the required configuration and construction.

By forming the arms in the manner stated, the arms can be configured as unit sections from a continuous length of tubing and afterwards cut to the required length for additional fabrication. By making the arms in this way, the tubing may be cold worked to maintain the high physical properties of the steel employed while the method is one which enables the sections to be rapidly and uniformly configured at a minimum of cost and at the same time it imparts the required shaping and wall thickness in such a way as to distribute the metal most advantageously in affording the required strength and rigidity.

Further objects and details will appear from a description of the invention in conjunction with the accompanying drawings, wherein:

Figure 1 is a view partly in elevation and partly in section showing one form of the housing of the present invention;

Fig. 2 a view of the channel section of material which is afterwards bent to circular shape to provide the circumferential wall of the drum-shaped "banjo" section;

Fig. 3 is a longitudinal sectional view of a unit of tubing as configured by the Dewey process and before being additionally fabricated to provide one of the tubular arms of Fig. 1.

Fig. 4 a cross sectional view taken on line 4—4 of Fig. 3 looking in the direction of the arrows;

Fig. 5 a similar view taken on line 5—5 of Fig. 1 looking in the direction of the arrows;

Fig. 6 is a view similar to Fig. 1 showing a modified form of construction;

Fig. 6a is a section of the channel section of Fig. 2, taken on line 6a—6a;

Fig. 7 view similar to Fig. 3 showing the section of tubing as configured by the Dewey method;

Fig. 8 a cross sectional view taken on line 8—8 of Fig. 7 looking in the direction of the arrows;

Fig. 9 sectional view of the tubular arm of Fig. 7 after final fabrication, and;

Fig. 10 cross sectional view taken on line 10—10 of Fig. 6 looking in the direction of the arrows.

Referring to Figs. 1—5 inclusive, the housing 15 as a whole consists of two tubular arms A which are connected by a drum-shaped intermediate "banjo" section B. Each of the arms in its completed form consist of an inner elliptical neck 21 which merges into an outwardly tapering section

20 22 which progressively approaches circularity and at its outer end merges into a cylindrical neck-like bracket section 23 which terminates in a first offset section 24 which in turn merges into a second offset section 25 which terminates in 25 an annular end flange 26 giving to the end of the arm a stepped formation.

The end flange is reinforced by a backing ring 27 spot welded thereto.

The inner neck 21 which is of maximum diameter is relatively thin-walled, while the wall of the tapering body 22 progressively increases in thickness and reaches a maximum thickness at the point of its emergence into the cylindrical bracket section 23 through which the thickened 30 wall extends while the wall of the stepped end portion of the arm progressively decreases in thickness being at a minimum in the peripheral flange 26.

The connecting drum-shaped "banjo" section 40 is formed from a length of channeled steel which is shown in its flat condition in Fig. 2 and which is provided with side flanges 28. The flat section at the proper points is apertured as indicated in the dot and dash ellipses in Fig. 2 and the surrounding metal is either hot or cold formed outwardly to provide an elliptical collar 29 of a size to closely surround and embrace the neck 21 of the associated tubular arm.

After the flat section of metal has been fabricated to the extent indicated in Fig. 2, it is bent to circular or drum-shaped form and the abutting ends spot welded at the joint 30 which together with the spot, arc or other welding 45 completes the housing.

In configuring the section of tubing by the

Dewey method, a length of tubing of uniform diameter and circular cross section is formed to the shape shown in Fig. 3 which at this stage is circular throughout with the tubing at the opposite ends 21a-26a of the original relatively thin walled thickness. During the shaping operation, the body portion 22a is tapered and the wall thickened down through the bracket section 23a and then flared and gradually thinned toward the end of the section.

It is desirable to configure a continuous length of tubing to provide a plurality of unit sections of the shape desired, which are thereafter cut to the proper length and each thereafter fabricated to give the resultant shape shown in Fig. 1.

The additional fabrication includes a flattening in of the sides of the body and neck portion of the configured section to give the required elliptical form and an additional spinning or forming to give the stepped or shouldered end formation, after which the unit section as a completed tubular arm is ready to be united with the intermediate "banjo" section formed in the manner described.

The tubular arm shown in Figs. 6-10 differs somewhat in its terminal form from that first described but its inner end which unites with the "banjo" section is identical therewith.

The body section instead of tapering uninterruptedly as in Fig. 1 is formed to merge into a straight bracket section 32 which, being a straight cylinder readily permits attaching brackets to be secured to the axle housing at this point. The bracket section is connected with an axle mounting neck-like section 33 through a tapered shoulder 34. The axle mounting section is shouldered or offset at the point 35 and terminates in a flange 36. The offset 35 and flange 36 afford a socket mounting for an axle flange 37 provided with a neck 38 which fits into the offset end of the arm and is spot welded thereto. The neck 38 on its interior lies flush with the inner wall surface of the axle mounting section and these two in conjunction afford a mounting for the inner end of a high-carbon axle stub 39 which is shouldered behind a flange collar 40 which affords a close contact with the rim of the neck 38 and the axle stub is spot welded at 41 to the surrounding axle mounting section. The outer end 42 of the axle stub is tapered and provided with threads 43. The arm of Fig. 6 is fabricated in a manner very similar to that heretofore described, in that a section of tubing of uniform wall thickness is formed to provide end portions 21a and 36a of the original diameter and minimum wall thickness with the attaching end 21a merging into a tapering body section 22a of increasing wall thickness which terminates in a bracket section 32a of cylindrical formation connected by a shoulder 34a with an axle mounting section 33a of maximum wall thickness which at its outer end is flared and progressively decreased in wall thickness to merge into the end section 36a. With the two thus configured, the side walls are flattened to the configuration shown in Fig. 9 and the stepped and flanged outer end portion is configured by a suitable spinning or forming operation which completes the arm in condition to receive the axle flange and axle stub.

The device of the form shown in Figs. 1-5 affords a mounting for a shaft which may be centered within ball or roller bearings (not shown) which are carried within the stepped outer end of the arm and in this way the driv-

ing wheel will be carried directly by the shaft in a manner well understood in the art.

In the construction shown in Figs. 6-10 the wheel will be mounted upon the axle stub rather than directly upon the shaft which is a form of construction likewise well understood in the art, and it is to make provision for the mounting of the shafting in either of these two ways that I have illustrated the two forms of construction heretofore described. In either case however the general form of the structure is otherwise the same.

By forming and fabricating the mounting sections in the manner described and preferably by a cold working process, the natural physical properties of the steel, such as 1010-15 carbon or similar steel are preserved so that the completed structure will possess elements of great strength combined with comparative lightness due to proper distribution of the metal and to variations in wall thickness which advantageously distributes the metal in such a way as to afford the necessary resistance to stresses at all points, and this is particularly true in the progressive flattening of the inner portions of the tubular arms to provide an elliptical formation with a maximum vertical diameter which adequately resists the vertical stress of the superposed load.

I claim:

1. The method of making rear axle housing arms for automobiles or the like which consists in first configuring an integral section of cylindrical tubing of uniform diameter and wall thickness by a reducing spinning operation to provide a unit of relatively greater diameter and relatively lesser wall thickness at its cylindrical attaching end and of relatively lesser wall thickness at its cylindrical terminal end and merging into an intervening body portion of tapering formation and increasing wall thickness away from its attaching end and merging at its outer end into a cylindrical neck-like section likewise of increased wall thickness but of minimum diameter and flared toward its outer end to unite with the cylindrical terminal end, thereafter by a separate operation flattening the walls of the attaching end and the body wall adjacent thereto to give to the attaching end a substantially elliptical uniform cross section throughout, with the merging body end progressively approaching a like degree of elliptical form, and by a separate operation forming down the flared portion of the neck-like section to produce an abruptly stepped formation and configuring the relatively thin walled terminal end to provide a peripheral flange.

2. The method of making rear axle housings for automobiles or the like, which consists in forming a "banjo" section from a straight strip of channel-shaped metal by forming spaced elliptical apertures therein, displacing the surrounding metal outwardly to provide attaching collars of substantially elliptical cross section, bending the strip to circular form and uniting the ends, forming two arms in each case by first configuring an integral section of cylindrical tubing of uniform diameter and wall thickness by a reducing spinning operation to provide a unit of relatively greater diameter and relatively lesser wall thickness at its attaching end and of relatively lesser wall thickness at its cylindrical terminal end and merging into an intervening body section of tapering formation and increasing wall thickness away from its attaching end and merging at its outer end into a cylindrical neck-like section likewise of increased wall thickness but

of minimum diameter and flared toward its outer end to unite with the cylindrical terminal end, thereafter by a separate operation flattening the wall of the attaching end and the body wall adjacent thereto to give to the attaching end a substantially elliptical cross section correlated with that of the attaching collar and with the merging body and progressively approaching a like degree of elliptical form, and by a separate

operation forming down the flared portion of the neck-like section to produce an abruptly stepped formation and configuring the relatively thin walled terminal end to provide a peripheral flange, and finally socketing together the elliptical attaching ends of the respective arms and the collars of the "banjo" section and uniting the attaching ends rigidly to the collars.

CLARENCE L. DEWEY.
